UNITED STATES PATENT OFFICE.

GEORGE P. DOHERTY, OF CHICAGO, ILLINOIS.

COPY-HOLDER.

1,172,681.

Specification of Letters Patent. Patented Feb. 22, 1916.

Application filed April 18, 1912. Serial No. 691,634.

To all whom it may concern:

Be it known that I, GEORGE P. DOHERTY, a citizen of the United States, and a resident of Chicago, in the county of Cook and State 5 of Illinois, have invented certain new and useful Improvements in Copy-Holders, of which the following is a specification, reference being had to the accompanying drawings.

10 This invention has relation to certain new and useful improvements in holders employed to give support and hold copy while being read, and includes a traveling spacing bar which is successively advanced as the 15 copy is read: and the object of my invention is to provide a device of this general character, of a simple and inexpensive nature and of a compact and durable construction, including a holding means for copy while the 20 traveling spacing bar shall be capable of convenient and accurate adjustment in position upon the copy, in a manner insuring the spacing bar at all times accurately registering with the lines of the copy, and my invention further includes an adjustable actuating mechanism for successively advancing 25 said spacing bar.

With these and other objects in view, the present invention consists in the combination 30 and arrangement of parts as will be hereinafter more fully described and finally pointed out in the appended claims, it being further understood that changes in the specific structure shown and described may 35 be made within the scope of the claims, without departing from the spirit of the invention.

In the accompanying drawings forming a 40 part of this specification and in which like numerals of reference indicate similar parts in the several views: Figure 1, shows a front elevational view of a copy holder embodying my invention. Fig. 2, is a side elevational view of Fig. 1. Fig. 3, is a top view. Fig. 4, 45 is a rear view. Fig. 5, is a sectional view through the supporting plate and pallet. Fig. 6, shows an enlarged perspective detail of the carriage with parts broken away. Fig. 7, is a central sectional view through the 50 carriage with portions broken away.

In my present invention I provide a simply constructed, readily operated device en-

abling typewriter operators, public speakers, proof readers, compositors and others to accurately follow copy; in that I provide an 55 apertured traveling spacing bar which is successively advanced over the copy, so that the consecutive line is always within the aperture of the spacing bar, thereby avoiding repetition or omission of a line in following the copy.

In the accompanying drawings the numeral 1 designates a suitable base to which is secured the standard 2, which has its upper end slotted as is shown at 5, in Fig. 4. 65 Extending transversely across the upper slotted end of the standard 2, is the bolt 3, carrying the wing nut 4, while pivotally held upon the bolt 3, is the ear 6, of the base plate 7, which by means of the screws 8, 70 is secured to the pallet 9. This pallet is preferably of sheet metal and has the two similar side flanges α , upper flange α' , and the lower flange α'' . Secured to the rear of the pallet and adjacent to one of the 75 flanges α , as shown in Fig. 4, is the preferably sheet metal supporting plate 10, which is secured to the pallet by any suitable means. At its upper end as shown clearly in Fig. 5, the supporting plate 80 10, has the apertured flange 14, extending at right angles to the plate 10, and ending in the curved upstanding stop collar 15. At its lower end the supporting plate 10, is continued in the apertured outstanding arm 11, ending in the ear 12, carrying the pin 13.

Slidably held within the apertures 2' and 1', of the members 14 and 11, shown in Fig. 5, is the trip-rod D, which has its upper end 90 threaded as shown at 17. Held upon the threaded end 17, is the stop nut 18, and the lock nut 19. At a suitable point below the stop nut 18, is located the tension nut 20, and interposed between this nut 20, and the 95 outstanding flange 14, is the coil spring 21, normally forcing the trip-rod D, upward. At its lower end this trip-rod D, is pivotally secured by means of the pin 16 shown in Fig. 5, to the spacing lever 41, which by 100 means of the pin 40, is pivotally connected to the link 39, carried upon the pin 13. As shown in Fig. 5, the lever 41, limits the upward movement of the trip-rod D. This

spacing lever 41, at its forward end is provided with the key 42 the rear end being bifurcated. The tension of the spring 21, is regulated by means of the nut 20, while 5 the downward movement of the trip-rod D, is regulated by means of the stop nut 18. Held in parallel spaced relation to the trip-rod D, are the two similar guide bars A and B, which are secured within the flange 14 and arm 11. Slidably held upon these two 10 guide bars A and B, is a carriage 23, having the flanges 8' and 9', shown in Fig. 5. By means of these flanges the carriage is accurately guided upon the bars A and B. In 15 front, the carriage is provided with the collar 2', encompassing the trip-rod D. In order to tensionally hold the carriage 23, to the bars A and B, I provide a curved spring 33, as shown in Fig. 7, which has its end 20 34, clamped upon the carriage and held by means of a screw 6'.

At a suitable point as shown in Fig. 6, the carriage is provided with the screws b and b', the first giving pivotal support to the 25 chisel-edged dog 24, while the remaining pin b', pivotally supports the chisel edged dog 25. These dogs are arranged to grip against the trip-rod D, as shown in Fig. 6, and are held against the rod by means of the springs 30 25', which are secured to the pins e and e'. In order to release the dogs I provide the releasing lever 28, this lever having the projecting operating end 29. Intermediate 35 of its ends, the releasing lever has two up-standing trip arms 30, 30, these arms being arranged to contact with the lower edges of the dogs 24 and 25. In order to control the downward movement of this releasing lever 28, I provide the carriage 23, with the stop 40 pin 4'. The upward movement of this releasing lever 28, is stopped by the pin e, shown in Fig. 6. Secured to the outer end of the carriage 23, is a bolt 34', shown in Fig. 6, which pivotally carries an arm 35, to the 45 end of which is pivotally secured by means of a pin 37, shown in Fig. 1, the apertured spacing bar 38.

As shown in the drawings, I secure to the upper edge of the pallet 9, a flange 50, and 50 secured centrally to this flange 50, is a U-shaped bearing yoke 46, which clasps upon the shaft 49. The yoke is secured by means of the pin 48'. This bearing yoke 46, prevents any lateral displacement of the screw 55 shaft 49, which at one end has a right handed thread and at the other end, a left handed thread, as shown in Fig. 4. One threaded end works within the pivotally held bearing block 45, while the opposite threaded end 60 works within the pivotally held bearing block 45'. An operating handle 59, is secured to the shaft 49. By means of suitable pivots 55, these bearing blocks 45, and 45', are pivotally connected to the ends 53, of 65 the clamps 54. These clamps in turn are

pivotally secured to the pins 51 and 52, held within the flange 50, this construction being clearly shown in Fig. 3. In turning the shaft 49, in one direction the clamps 54, are carried away from the pallet while rotation 70 in opposite direction carries the clamps against the pallet. These clamps are used to hold the copy to the pallet, and in Fig. 1, a sheet α , is shown as clamped to the pallet 9.

By means of the stop nut 18, the distance 75 traveled by the spacing bar 38, may be accurately adjusted. The spacing bar can further be accurately adjusted to the copy in simple raising up the lever 28, which carries the dogs out of engagement with the 80 trip-rod, D. In order to raise and lower the carriage, it is simply necessary to overcome the friction of the spring 34, against the bar A. As soon as the spacing bar has been properly adjusted the lever 28, is released when the dogs 24 and 25, again bite against the trip D. Then on depressing the spacing lever 41, the trip D, is carried downward and as the chisel edged dogs are in contact with the bar the entire carriage is 90 carried downward. On releasing the trip-rod D the spring 21, promptly forces this rod upward, the rod escaping below the chisel edges of the dogs, which are moved upward, permitting the rod to escape. The 95 downward movement of the dogs is of course controlled in their coming in contact with the rod D.

From the foregoing it will be understood that by means of the nut 18, the movement 100 of the spacing bar may be accurately regulated so that the spacing bar will accurately feed down the copy, at each stroke of the operating lever 41.

Copy holders embodying my invention 105 may be made in various sizes. The device is simple and inexpensive in construction both durable and efficient in operation and the copy can be instantly and accurately secured to the pallet while the adjustment of 110 the spacing bar is effected with ease, accuracy and despatch.

Having thus described my said invention, what I claim as new and desire to secure by United States Letters Patent is:

1. In combination, two parallel guide bars, a carriage slidably held upon said bars having a collar, a trip rod slidably held within said collar, two dogs pivotally secured to said carriage having their ends 120 contacting with said trip rod, springs to normally hold said dogs to said trip rod, a releasing lever pivotally secured to said carriage below said dogs having two upstanding arms arranged at times to contact with 125 said dogs, a pin limiting the downward movement of said lever, and means limiting the upward movement of said lever.

2. In combination, two parallel guide bars, a carriage slidably held upon said bars 130

having a collar, a trip rod slidably held within said collar, two dogs pivotally secured to said carriage having their ends contacting with said trip rod, springs to normally hold said dogs to said trip rod, a releasing lever pivotally secured to said carriage below said dogs having two upstanding arms arranged at times to contact with

said dogs, and a pin limiting the downward movement of said lever. ¹⁰

In testimony whereof I affix my signature, in presence of two witnesses.

GEORGE P. DOHERTY.

Witnesses:
